UNITED STATES PATENT OFFICE.

JOHN FINDLEY, OF DE SOTO, KANSAS.

PIPE-WRENCH.

1,390,112.

Specification of Letters Patent. Patented Sept. 6, 1921.

Application filed April 15, 1921. Serial No. 461,466.

To all whom it may concern:

Be it known that I, JOHN FINDLEY, a citizen of the United States, residing at De Soto, in the county of Johnson and State of 5 Kansas, have invented certain new and useful Improvements in Pipe-Wrenches, of which the following is a specification.

My said invention relates to an improvement in pipe wrenches and it is an object of 10 the same to provide a device of this character which may be adjusted with great readiness and which shall operate with certainty.

Referring to the accompanying drawings, which are made a part hereof and on which 15 similar reference characters indicate similar parts,

Figure 1 shows my device in perspective, and

Fig. 2 is an elevation of the same in working relation.

In Fig. 1 reference character 5 indicates the body of the wrench having an enlarged handle 6 and a terminal jaw 7. The handle is grooved at its front side at 8 and the jaw 25 is also grooved as at 9. A slideable bracket 10 embraces the body and has a flat face 11 rounded off at the ends and bearing against the back of the body. At its forward end the bracket carries a pivot 12 on which is a 30 rotary device 13. This device has teeth 14 with notches between them, these teeth being adapted to engage with the teeth between notches 8 for adjustment of the rotary member 14 relative to the jaw 7. In this 35 manner the rotary device forms a pinion co-acting with rack-teeth on the body 5 for adjustment while at the same time the member 14 constitutes the rear jaw of the wrench.

As will be evident from the drawings the ridges on the jaw 7 coöperate with the 40 ridges on the member 14 to grip the surface of a piece of pipe or other cylindrical work 15 in the usual manner. When the wrench is turned in the direction of the arrow the jaws 9 and 14 will tend to turn in the direction of the arrow 16 and thus grip the pipe with increasing force. A reverse movement 45 of the wrench will loosen the jaw 14 and start to back it off from the work and it may then be moved back with its bracket 10 to release the wrench from the work. 50

Having thus fully described my said invention, what I claim as new and desire to secure by Letters Patent, is:

A wrench having a body, an enlarged 55 handle thereon, an integral jaw projecting at an angle from the body and having a roughened face, a bracket slideably embracing the body provided with a flat face and rounded off ends and bearing against the back of the body, a rotary member carried by said bracket having a roughened face to form the opposing jaw of the wrench, the roughened face of said member co-acting with the roughened face on the body of the 60 wrench to lock the movable jaw in adjusted 65 position, substantially as set forth.

In witness whereof, I have hereunto set my hand and seal at De Soto, Kansas, this 11th day of April, A. D. nineteen hundred and 70 twenty-one.

JOHN FINDLEY. [L.S.]

Witnesses:

HARRY E. MILLER,
C. S. HAMBLETON.
